United States Patent Office

Des. 191,228
Patented Aug. 29, 1961

191,228

TELEVISION RECEIVER OR SIMILAR ARTICLE

Satoshi Shimada, Tokyo, Nobuo Kitamura, Kanagawa,
and Tadashi Saito, Tokyo, Japan, assignors to Sony
Corporation, Tokyo, Japan, a corporation of Japan

Filed June 20, 1960, Ser. No. 61,026

Claims priority, application Japan Mar. 14, 1960

Term of patent 14 years

(Cl. D56—4)

FIGURE 1 is a front perspective view of the television receiver, or similar article, showing our new design;

FIGURE 2 is a rear elevational view thereof.

FIGURE 3 is a side elevational view thereof.

The dominant features of our design reside in the portion shown in full lines.

We claim:

The ornamental design for a television receiver or similar article, substantially as shown and described.
